J. L. ORR.
BAG FASTENER.
APPLICATION FILED FEB. 8, 1917.

1,243,865.

Patented Oct. 23, 1917.

UNITED STATES PATENT OFFICE.

JOSEPH L. ORR, OF LYNCHBURG, VIRGINIA.

BAG-FASTENER.

1,243,865.

Specification of Letters Patent. Patented Oct. 23, 1917.

Application filed February 8, 1917. Serial No. 147,400.

To all whom it may concern:

Be it known that I, JOSEPH LAWRENCE ORR, a citizen of the United States, residing at Lynchburg, in the county of Campbell and State of Virginia, have invented certain new and useful Improvements in Bag-Fasteners; and I do declare the following to be a full, clear, and exact description of the invention, such as will enable others skilled in the art to which it appertains to make and use the same.

This invention relates generally to fasteners and more particularly to certain new and useful improvements in fasteners for bags.

The primary object of the invention is to provide a fastener for fastening the draw string of a bag or the like after the string has been drawn tight upon the mouth of the bag.

Another object of the invention is to provide a device of this character which will be of extremely simple and inexpensive construction, yet one which will be strong, durable, and well adapted to the purpose for which it is designed.

With these and other objects in view, the invention resides in the details of construction and the combination and arrangement of parts as will be hereinafter fully described and claimed.

In the accompanying drawings forming a part of the application:

Figure 1 is a perspective view of the upper end or mouth of a bag having a draw string, illustrating the application of a device constructed in accordance with this invention thereto;

Fig. 2 is a top plan view of the device, partly in section, detached from the bag but showing the manner in which the draw string is connected to the same ready to be drawn;

Fig. 3 is a central vertical longitudinal sectional view of the fastener taken on the plane indicated by the line 3-3 of Fig. 2; and;

Fig. 4 is a perspective view of the fastener and the draw string, showing the latter ready to be wound around the shank of the fastener and clamped.

In describing the structure of the invention shown in the drawings above briefly described, similar reference characters will be placed on like parts throughout all the views, and reference will be herein made

to the various elements by their respective indices. To this end, the numeral 1 designates a body member or head which in the present instance is of rectangular configuration, but which, it is to be understood, may be of any desired shape. Extending transversely from edge to edge through the head 1 is a pair of parallel apertures 2, the purpose of which will be hereinafter described.

Extending laterally from one of the above mentioned edges of the head 1 from a point disposed between one of the ends of the apertures 2 is a shank 3. This shank 3 is formed integrally with the head 1, and is bifurcated, the furcations of which are provided on their inner sides with opposing recesses 4. These recesses 4 coöperate to form in effect a chamber which is disposed inwardly of the free end of the furcations 75 of the shank, said free ends of said furcations being beveled inwardly as at 5 from their outer to their inner sides for a purpose to be described.

While the fastener may be made up of any material, yet a slightly resilient metal is convenient, and wood, while being cheaper than metal, is preferred. In the drawings the fastener is shown as being constructed of wood.

While the device is applicable for use in connection with receptacles other than bags, yet for the purpose of illustration it is shown in Fig. 1 in connection with a bag A.

This bag is provided with a draw string B which is connected to the same in the usual manner. The ends of the draw string B are inserted through the apertures 2 in the head 1 and tied together as at b to prevent the head 1 from being accidentally disengaged.

After the bag has been filled or it is desired to close it, the draw string B is drawn through the apertures 2 until tight. It is then wound around the shank 3 a number of times, and the ends of the string are then passed between the furcations in the shank and disposed in the chamber formed by the recesses 4 in the inner side of said furcations.

The shoulders formed at the outer ends of the recesses 4 provide a means for preventing the string from sliding longitudinally with respect to the shank, and yet are not of sufficient depth to allow said string to be loosely clamped. The beveled ends 5 of the furcations of the shank provide a ready means for inserting the string between the same. When clamped in

this manner, the draw string will be prevented from accidentally loosening, and yet may be easily disengaged from the fastener and loosened. The portions of the draw 5 string B wound around the shank 3 provide an efficient means for preventing the furcations of said shank from separating with respect to each other and for causing them to effectively engage the portion of said 10 string disposed between them.

The device is especially applicable to laundry bags, and in this connection it will be found convenient to provide a tag holding means. Such a means is shown in the 15 drawings consisting of a spring fastener C, one of the members of which is secured to the head 1 by means of a screw or other securing device e. In Fig. 1 of the drawings, a tag D is shown clamped between 20 the jaws of the fastener C.

The head and shank being integrally united as above described and shown in the drawings present as a whole a T-shaped structure in plan view.

25 From the foregoing description taken in connection with the accompanying drawings, the construction and use of the invention will be understood without a more extended explanation.

30 As various changes in form, proportion, and in the minor details of construction may be resorted to without departing from the spirit of this invention, it is to be understood that I do not wish to be limited to the 35 construction herein shown and described other than as claimed.

I claim:

40 1. A device of the class described comprising a head provided with a pair of apertures, and a bifurcated shank attached to said head, the furcations of said shank being resilient, in combination with a draw string extending through said apertures and wound around said shank, and then clamped 45 between the furcations thereof, the portions of said draw string which are wound around said shank holding the furcations thereof in their clamped positions.

50 2. A device of the class described comprising a head having a pair of transversely

extending parallel apertures, and a bifurcated shank extending laterally from one edge of said head and disposed between said apertures, the furcations of said shank being provided with opposing recesses in their inner sides, in combination with a draw string extending through said apertures and wound around said shank, and then clamped between the opposing recesses of said furcations, the shoulders formed at the outer ends 55 of said recesses preventing said string from moving longitudinally with respect to said furcations.

3. A device of the class described comprising a head having a pair of apertures 60 extending therethrough, and a bifurcated shank extending laterally from one edge of said head and disposed between said apertures, said shank being integrally united with said head and combining with the latter to form a T-shaped structure, in combination with a draw string extending through said apertures and wound around said shank, and then clamped between the furcations thereof, the portions of said draw 70 string which are wound around said shank holding the furcations thereof in their clamped positions.

4. A device of the character described comprising a head having a pair of cord receiving openings and a bifurcated shank extending from said head, the furcations of said shank being resilient for the purpose 80 set forth.

5. A device of the character described comprising a T-shaped structure including 85 a head and a shank projecting therefrom, said head being formed with a pair of parallel apertures arranged adjacent its ends and said shank being arranged between said 90 apertures and bifurcated to provide resilient members for the purpose set forth.

In testimony whereof I have hereunto set my hand in the presence of two subscribing witnesses.

JOSEPH L. ORR.
